UNITED STATES PATENT OFFICE.

THOMAS J. O'LOUGHLIN AND HENRY E. SMITH, OF CHICAGO, ILLINOIS.

FIRE POT.

Application filed November 13, 1919. Serial No. 337,802.

To all whom it may concern:

Be it known that we, THOMAS J. O'LOUGHLIN and HENRY E. SMITH, citizens of the United States, residing at Chicago, 5 in the county of Cook and State of Illinois, have invented new and useful Improvements in Fire Pots, of which the following is a specification.

This invention relates to fire pots or furnaces used by plumbers, tinners and other mechanics, and more particularly an appliance of this kind using liquid fuel, such as gasoline or kerosene, and constructed on the order of the furnace shown in Patent No. 15 1,090,009 of Mar. 10, 1914 to A. J. Archambault.

The invention has for its object to provide the appliance with certain novel and improved structural details to be herein- 20 after described and claimed, and in order that the same may be better understood, reference is had to the accompanying drawing forming a part of this specification.

In the drawing, 25 Figure 1 is a plan view of the part which is the subject matter of the present application for patent;

Fig. 2 is a side elevation thereof, and

Fig. 3 is a section on the line 3—3 of 30 Fig. 1.

Referring specifically to the drawing, 5 denotes a top plate having lugs 6 for holding the usual shield (not shown) on said plate, these parts corresponding, respectively, to the plate 17 and the shield above it in the patent referred to. Beneath the top plate, in line with a central opening 7 therein, is located the vaporizing coil or retort 8, the same being surrounded by a hood 40 or jacket 9. Ordinarily, this hood or jacket is of sheet metal and separate from the cast top plate and bolted or otherwise secured thereto.

The heat to which the hood and the fasteners are subjected is so extreme that the hood soon becomes distorted or cracks loose from the top plate, and the fasteners become tightly jammed, requiring them to be cut away to permit the removal of the damaged hood or clinging sections thereof. Inasmuch as the hood is ordinarily made integral with the burner chamber below, the condition described makes it necessary to replace the entire hood and burner chamber, 55 even though the latter on account of its

remoteness from the flame may still be in good condition.

In order to avoid the labor and expense involved in a repair of the nature described, the hood in the improved structure is made 60 integral with the top plate but separate from the burner chamber 10. Thus, the hood is cast in one piece with the top plate, and is of sufficient thickness to enable it and the top plate to withstand extreme heat 65 for a long time. When corroded or cracked, the casting could easily be replaced at small expense and with little labor. The sheet metal burner chamber is applied to the lower end of the hood by a detachable connection, which consists of providing the lower end of the hood with headed side studs 11 which seat in bayonet slots 12 in the top edge of the burner chamber 10. Thus, after giving the latter a slight twist 70 it may be slipped off the hood 9, and by a reversal of this operation it can be easily replaced. An enclosure is thus had in which the section subjected to extreme heat is durable and easily replaced at small expense, 80 and in which the section enclosing the burner is easily removable for access to the burner and coil, and is not affected by damage to the section which is subjected to heat. It will be noted that the parts 9 and 10 are 85 tapered, the taper of the part 9 being downwardly so that the larger top portion of the member 10 may be mounted to embrace the smaller bottom portion of the member 9. This taper is important as it facilitates 90 the removal of the member 10 from the member 9.

The fuel reservoir and other parts of the complete appliance have not been illustrated as they form no part of the present invention. 95

We claim:

1. A device of the kind described comprising a tapered tubular body member having an integral radial flange at its larger 100 top end forming a top plate, and means providing a combustion chamber extension adapted to be detachably secured to the bottom end of said tubular body.

2. A device of the kind described, comprising a tapered tubular body member having an integral radial flange at its larger 105 top end forming the top plate, and a sheet metal combustion chamber extension carried by the bottom end of said tubular body, 110

said combustion chamber extension and last mentioned end of said body having coacting attaching means by which the combustion chamber extension is detachably secured to the tubular body.

3. A device of the kind described comprising a tapered tubular body which is larger in diameter at its top end than at its bottom end, said top end terminating in a radial flange providing a top plate, a similarly tapered combustion chamber extension

adapted to embrace the smaller bottom end of said tubular body, said bottom end of said body and top end of said combustion chamber extension having coacting bayonet 15 slot attaching devices by which said combustion chamber extension is removably attached to the body member.

In testimony whereof we affix our signatures.

THOMAS J. O'LOUGHLIN.
HENRY E. SMITH.
